UNITED STATES PATENT OFFICE.

HERBERT O. SPADE AND HENRY E. SPADE, OF VICKSBURG, MICHIGAN.

OIL-FEEDING OR CHARGE-DELIVERING DEVICE.

No. 817,997.

Specification of Letters Patent.

Patented April 17, 1906.

Application filed February 10, 1905. Serial No. 245,154.

To all whom it may concern:

Be it known that we, HERBERT O. SPADE and HENRY E. SPADE, citizens of the United States, and residents of Vicksburg, in the county of Kalamazoo, State of Michigan, have invented certain new and useful Improvements in Oil-Feeding or Charge-Delivering Devices, of which the following is a specification.

10 This invention relates to improvements in oil-feeding or charge-delivering devices.

Our invention is particularly adapted as a liquid hydrocarbon feeding or charging device for explosion-engines, although it is very 15 desirable for use as an oil-feed or charge device for lubricators, and is also adapted for use in other relations.

The objects of this invention are, first, to provide an improved feed device of the class 20 described adapted to deliver a fixed amount at each charge; second, to provide an improved feed device of the class described, in which the amount delivered is under perfect control; third, to provide an improved feed 25 device of the class described adapted to accomplish the results specified which is very simple and economical in structure and durable in use.

Further objects and objects relating to 30 structural details will definitely appear from the detailed description to follow.

We accomplish the objects of our invention by the devices and means described in the following specification.

35 The invention is clearly defined, and pointed out in the claims.

A structure embodying the features of our invention is clearly illustrated in the accompanying drawings, forming a part of this specification, in which—

40 Figure 1 is a detail longitudinal sectional view of our improved oil-feeding or charge-delivery device, the plunger being shown in full lines with its charge pocket or receptacle in its charging position, the discharging position being indicated by dotted lines. Fig. 45 2 is a detail longitudinal sectional view corresponding with that shown in Fig. 1 with the plunger shown in full lines with its charge pocket or receptacle in its discharged position. Fig. 3 is a longitudinal sectional view taken on line 3 3 of Fig. 1 looking in the direction of the little arrows at the ends of the section-line.

In the drawings similar letters of reference 55 refer to similar parts throughout the several views.

Referring to the drawings, a cylinder A is provided. This cylinder is provided with a receiving passage or chamber a, and a discharge or delivery passage or chamber a'. The receiving-passage a of the cylinder is connected by the pipe B to a suitable supply or storage. (Not here illustrated.) The delivery-passage a' is connected to the mixing chamber or cylinder of the engine when the device 60 is used as a charging device for explosion-engines, or to the part to be lubricated when the device is used as a lubricator, the parts not being here illustrated, by the pipe B'. 70

A plunger C, having a charge pocket or receptacle c, is provided. As the plunger C is reciprocated this pocket or receptacle c is brought alternately into the receiving and discharge passages a a' of the cylinder. The plunger C is provided with a relatively fixed head portion C' at its inner end, and with a sleeve C'' at its outer end. The sleeve C'' contacts with the head C' in forming the annular groove-like charge-pocket c. The head C' and the sleeve C'' are of the same diameter and form, in effect, a plunger with a relatively fixed part and a reciprocating part. The outer or sleeve end of the plunger C projects through the stuffing-box A'. The outer end 75 of the plunger is threaded to receive the nut D, by which the sleeve C'' is retained in position and its stroke controlled. This nut D is preferably split and is provided with a set-screw d, by means of which it is clamped in its 80 adjusted position. As the plunger C is reciprocated the sleeve C'' shifts back and forth, alternately contacting with the head C' and with the nut D. When the sleeve is in contact with the nut D, the pocket c is 85 fully open, and when the sleeve is in contact with the head portion C' of the plunger the pocket is closed. (See Figs. 1 and 2.) With the parts thus arranged by adjusting the nut D the size of the charge-pocket is 90 controlled, thereby regulating the size of the charge. 95

On the inner end of the cylinder A is a gear-casing E for the driving-gear of the plunger. This driving-gear preferably consists of the driven shaft F, having a disk-like wheel F' on its inner end. A pitman-pin f, carried by the wheel, engages the slot c' in the head 100 105

of the plunger. By thus arranging the plunger, the charge-pocket thereof is opened in the receiving-passage to receive the charge and closed or collapsed in the discharge-passage, thereby forcing the charge therefrom.

With the parts in the position shown in Fig. 1 the plunger has completed its out-stroke and is on the instroke, the pocket beginning to open as soon as the instroke begins by the drawing away of the head portion C' from the sleeve C". The pocket is thus caused to open in the supply-passage, thereby causing a vacuum, which insures its prompt filling.

When the plunger is in the position shown by dotted lines in Fig. 1, the pocket opens into the discharge-passage. As soon as the plunger begins its outstroke the pocket begins to close, as the sleeve portion C' of the plunger is held by the friction of the stuffing-box A' until it is engaged by the head portion C", so that the pocket is completely closed, thus completely ejecting the charge therefrom. (See Fig. 2, where the pocket is illustrated in its closed position.) We thus secure in a simple manner the positive charging and discharging of the plunger at each stroke. The pocket is carried into the charging chamber or passage in its closed position, so that no air is delivered thereto. This is of great advantage, as otherwise it is necessary to provide means for the escape of the air, and particularly in the case of feeding heavy liquids or oils the air prevents the ready filling of the pocket. In this structure the pocket being opened in the charging-passage it creates a vacuum and is readily filled. The pocket is positively closed in the discharge-passage. The charge is forced therefrom, although the same may be of very heavy or thick material, such as heavy oils. By adjusting the nut D the size of each charge may be regulated as desired.

We have illustrated and described our improved charge-delivery device in the form preferred by us on account of its structural simplicity and economy and convenience in adjustment. We are, however, aware that it may be considerably varied in structural details without departing from our invention.

Having thus described our invention, what we claim as new, and desire to secure by Letters Patent, is—

1. The combination of a cylinder having receiving and discharging passages therein; a plunger for said cylinder having a relatively fixed portion and a sleeve-like portion reciprocatingly mounted thereon and coacting therewith to form a charge pocket or receptacle; a nut on said plunger, controlling the stroke of the sleeve thereon, thereby controlling the size of the said charge-pocket; and means for reciprocating said plunger, whereby said sleeve is shifted to alternately open said

charge-pocket in said receiving-passage, and to close the same in said discharge-passage, for the purpose specified.

2. The combination of a cylinder having receiving and discharging passages therein; a plunger for said cylinder having a relatively fixed portion and a sleeve-like portion reciprocatingly mounted thereon and coacting therewith to form a charge pocket or receptacle; and means for reciprocating said plunger, whereby said sleeve is shifted to alternately open said charge-pocket in said receiving-passage, and to close the same in said discharge-passage, for the purpose specified.

3. The combination of a cylinder having receiving and discharging passages therein; a plunger for said cylinder having a relatively fixed portion and a sleeve-like portion reciprocatingly mounted thereon and coacting therewith to form an annular charge pocket or receptacle; means for controlling the stroke of said sleeve; and means for reciprocating said plunger, whereby said sleeve is shifted to alternately open said charge-pocket in said receiving-passage and to close the same in said discharge-passage, for the purpose specified.

4. The combination of a cylinder having receiving and discharging passages therein; a plunger for said cylinder having a relatively fixed portion and a relatively movable portion reciprocatingly mounted thereon and coacting therewith to form a charge pocket or receptacle; means for controlling the stroke of the said relatively movable portion of said plunger, thereby controlling the size of said charge-pocket; and means for reciprocating said plunger, whereby said charge-pocket is alternately opened in said receiving-passage and closed in said discharge-passage, for the purpose specified.

5. The combination of a cylinder having receiving and discharging passages therein; a plunger for said cylinder having a relatively fixed portion and a relatively movable portion reciprocatingly mounted thereon and coacting therewith to form a charge pocket or receptacle; and means for reciprocating said plunger, whereby said charge-pocket is alternately opened in said receiving-passage and closed in said discharge-passage, for the purpose specified.

6. The combination of a cylinder having a receiving and a discharging passage therein; a plunger for said cylinder having a charge pocket or receptacle arranged to pass from said receiving-passage to said discharge-passage; a movable part on said plunger adapted to open said pocket in said receiving-passage, and to close the same in said discharge-passage, controlled by the movement of said plunger; and means for reciprocating said plunger, for the purpose specified.

7. The combination of a cylinder having a receiving and a discharging passage therein;

a plunger for said cylinder having a charge
pocket or receptacle arranged to pass from
said receiving-passage to said discharge-pas-
sage; a movable part arranged to open said
5 pocket in said receiving-passage, and to close
the same in said discharge - passage; and
means for reciprocating said plunger, for the
purpose specified.

In witness whereof we have hereunto set
our hands and seals in presence of two wit- 10
nesses.
